V-BLOCK

John R. Sasek, Edwardsville, Ill., assignor to The
L. S. Starrett Company, Athol, Mass., a cor-
poration of Massachusetts

Application July 2, 1934, Serial No. 733,437

3 Claims. (Cl. 77—63)

This invention relates to work holders and particularly those of the type generally known as V-blocks for clamps and guides for round or irregular stock.

5 These blocks are made with detachable, adjustable U-shaped clamp members and are generally square or oblong blocks milled out with different sizes of V-shaped openings. Such blocks have been made invertible so as to give 10 two or more, or in a well known type of block, four work clamping faces substantially X-shaped in cross section, to increase the range of stock diameter that can be accommodated.

Whenever the clamp is used simply as a clamp 15 or as a guide, the problem is to hold the block on the bench, lathe, machine platen or magnetic chuck. This is done usually by the mechanician's clamp, but such a holding basis was clumsy and cumbersome and not adapted to 20 varieties of positions or postures of work.

My concept includes a novel one of versatile posture so that the same block can be readily held in different positions and at relative angles of working axes. This I accomplish by a 25 simple departure from the present blocks by providing for a clamping at a stepped end at right angles to the main top V-groove and for varied posture mountings so that even a simple two V-block may be used for a great variety of 30 work and at different angles, for any of the usual operations, such as filing, stamping, grinding, laying out or driving pins, where the mechanician desires to hold a round or irregular piece of stock.

35 The forms shown in the accompanying drawings are practical interpretations of my invention and well adapted to manufacture on a production basis. These forms are to be understood as advantageous but not shown as limit- 40 ing.

In the drawings:—

Fig. 1 is a general view of a work block in accordance with my invention with clamp detached.

45 Fig. 2 is a diagrammatic section suggestive of the distribution of lines of force or resultants.

Fig. 3 is an end view.

Fig. 4 is a side view of the block shown in Fig. 1 with clamp removed.

50 Fig. 5 is a plan view with the clamp in position on the end step, and

Fig. 6 is a central longitudinal section through the block showing the threaded attachment and clearance apertures.

55 In the forms shown the blocks consist pref-

erably of relatively long base portion 1 made thin at a waist line or valley 2 between it and the upper portion 3.

As shown in the drawings, this upper portion 3 is shorter than the base portion 1 and more nearly square except that it is provided with a top V-groove 4 as in the old home-made machinists' blocks.

The top of the upper portion 3 is shouldered as at 5 and extends as an undercut beneath the 10 jaw of the V as at 5¹. This provides a slideway for the usual clamp member 10 but brings its foot 11 in close to the central perpendicular of the V-cut 4. The foot 11 has a flat bottom or face 11a which bears on the upper surface 5 15 and is slidably adjustable along it.

This makes a strong clamp assembly as the 20 foot 11 of the adapted conventional inverted U-clamp 10 (see diagrammatic indication Fig. 2) lies not only on the top of the upper block portion 3 so as to be slidably supported along its upper surface, but its foot end 11 presents a close 25 parallel support to the V face 4. In fact, as I have indicated at X (Fig. 2) the foot end 11 may be made with an angular face parallel to the face of the V cut 4. The clamping pressure P is applied by a screw 12 or any other substitute clamping means.

In the drawings I have shown a boss 10¹ (Fig. 30 1) tapped to receive the clamp screw 12 when the block is being leveled on a flat surface. It will be noted that the upper portion 3 is of less width so that when the block is laid on its side the screw 12 when positioned as in Fig. 3 may be used to level the whole block relative to any 35 surface.

This carries out geometrically because as indicated in Fig. 2 any larger (or smaller) piece of shaft or stock will have its center C still in the vertical axis of the V. Mechanically this is the 40 line of thrust P of the screw 12 of the slidable and shiftable clamp frame 10.

The base portion 1 has its stepped end 13 provided with the usual V notch 14. Its end face 15 is also provided with an undercut 15¹ for the clamp end 11 as shown in Fig. 5, and suggested in Fig. 1. This latter figure is intended to indicate the interchangeability of the clamp frame 10 from top to end position on the block.

While my base portion 1 may be clamped 50 down by contact with the upper surface 1b of the valley or the transverse surface 1c at the end of the block or by contact with the stop portion 1a, however, to increase the range of usefulness 55 of my new block I provide for other postures and

5 manners of mounting. For example, as shown at 30, 31 and 32 (best observed in Fig. 6) I provide threaded apertures for clamp bolts conventionally indicated in Figs. 3 and 4 which might be used to clamp the block to a usual angle iron or tool maker's knee suggestively indicated in fragmentary section at K in Fig. 4. The tapped aperture 30 is carried through at 30a and the tapped aperture 31 is also carried through at 31a as indicated at Fig. 6. The clearance 31a particularly provides for knocking pins out of work while clamped in the groove 4.

The design of the present V-block provides for a wide range of work posture in the lathe or the drill press or work table or on the usual angle iron or tool maker's knee. The blocks are of simple design and can be produced almost as cheaply as the old types.

The V or other shaped work receiving recesses 20 4 or 14 may be of any size desired or may be combined in sets with different clamp screws for heavier or lighter work or with the drill guides or bushings before described.

25 While I have shown in the accompanying drawings specific forms of block, clamp and bushing bases as illustrative of the practical development of my invention, the same is not considered to be limiting in any way.

What I therefore claim and desire to secure by
30 Letters Patent is:—

35 1. A work holder comprising a block including a base portion and an upper portion, the base portion being of greater length than said upper portion, and extending at least at one end beyond the adjacent end of the upper portion and forming a step therewith, said extended base portion having a V-groove in the end thereof and also having adjacent undercut grooves to accommodate the foot portions of a work clamp, the

upper portion having a V-groove in the top thereof disposed at right angles to said first mentioned V-groove and also having adjacent undercut grooves to accommodate the foot portions of a work clamp, the clamp receiving grooves of the upper portion and of the end extension of the base portion being of a depth and spacing to interchangeably accommodate a single work clamp.

2. A work holder as set forth in claim 1 in which a groove is formed in the sides of the block and across the end thereof remote from the end extension of the base portion and provides a shoulder extending along each side and across the last mentioned end of the block to be engaged by means for clamping the block to a support.

3. A work holder comprising a block including a base portion and an upper portion, the base portion being of greater length than the upper portion and extending above the upper portion.

tion and extending at one end beyond the adjacent end of the upper portion and forming a step therewith, the opposite ends of the base and upper portions being flush with each other, said

upper portions being flush with each other, said extended base portion having a V-groove in the end thereof and also having adjacent undercut grooves to accommodate the foot portions of a work clamp, the upper portion having a V-groove in the top thereof disposed at right angles

groove in the top surface impaled at right angles to said first mentioned V-groove and also having adjacent undercut grooves to accommodate the foot portions of a work clamp, said block, below the last mentioned grooves, having side grooves

and a groove in the end thereof remote from the end extension of the base to provide a shoulder extending along the sides and across the last mentioned end of the block, flush with the top surface of the end extension of the base portions.

JOHN R. SASEK.
